W. GOETZ.
WIRE ROPE SECURING MEANS.
FILED SEPT. 22, 1920.

FIG. 2.

FIG. 3.

WILLIAM GOETZ

FIG. 4.

By Fred G. Detenbeck, Jr.
Attorneys

UNITED STATES PATENT OFFICE.

WILLIAM GOETZ, OF VANCOUVER, BRITISH COLUMBIA, CANADA.

WIRE-ROPE-SECURING MEANS.

Application filed September 22, 1920. Serial No. 412,079.

To all whom it may concern:

Be it known that I, WILLIAM GOETZ, citizen of the Dominion of Canada, residing at Vancouver, in the Province of British Columbia, Canada, have invented certain new and useful Improvements in Wire-Rope-Securing Means, of which the following is a specification.

This invention relates to a wire rope securing means which has been particularly designed to enable a wire rope guy or the like to be tightened in its connection to its anchorage, and for securing it in that tightened condition.

The invention is particularly described in the following specification, reference being made to the drawings by which it is accompanied, in which:

Fig. 1 is a side elevation of the device as connected to tighten a rope, the full lines showing it in the position as when tightening, and the dot and dash lines as when the tightening is effected and the device secured.

Fig. 2 is a plan of the same.

Fig. 3, an end elevation looking in the direction of the arrow 3, and

Fig. 4 is a cross section to an enlarged scale on the line 4—4 in Fig. 1.

In these drawings 2 represents a wire rope guy line which it is required to tighten in its connection to its anchorage. This wire rope is passed around a grooved sheave 4 which is rotatably mounted between side frames 5, between which frames a shackle or eye 6 is mounted by which the device is connected to its anchorage, preferably by means of a releasable hook, such as is the subject of a co-pending application.

The guy rope 2 is taken over the upper side of the sheave 4 and passes from the underside, as at 3, between the jaws of a clamp 7, 8 to the donkey engine or other power means by which the guy rope 2 is to be tightened.

The upper clamp member 7 is integral with or secured between the side frame plates 5 and the lower member 8 is pivoted at 9 to lugs projecting downward from the side plates adjacent the sheave 4. One of these clamp members has a convex projection 10 which fits a corresponding concavity in the other clamp member, and the adjacent parts of both clamp members are longitudinally grooved to receive the rope, so that the rope on being clamped is bent

around the projection 10 and a better grip is thereby obtained of the rope.

The slack end 3 of the rope is retained alongside that portion 7 of the clamp member which is integral with the side frames 5 in which the sheave 4 is mounted, by a fair lead sheave 15 connected by links 16 to a pin 17 across the end of the clamp 7, which end is enlarged, as at 18, to retain it.

The lower clamp member 8 is drawn up to 7 to clamp the rope between them by bolts 11 pivotally connected to lugs projecting from each side of 8, which bolts pass between corresponding lugs 13 projecting from the clamp member 7.

The sheave 4 is provided with ratchet teeth 19 on one or both sides of the groove, which teeth are engaged by a pawl 20 mounted in the frame 5 and prevents the sheave rotating backward. By thus securing the sheave against rotation backward, the frictional hold of the rope around the half circumference of the sheave will relieve the strain imposed on the clamp.

In use the shackle 6 being connected to the anchorage, and the guy rope 2 passed around the sheave 4 and between the clamp members 7 and 8 over the sheave 15, tension may be imposed on the end 3 of the rope to tighten the guy rope 2. When the desired tension has been imposed on the rope, the bolts 11 are upwardly turned to engage the lugs 13 and the clamp member 8 is drawn tightly toward 7 to secure the rope between them in its tightened condition. When this is accomplished the fair lead sheave 15 may be removed and the end 3 of the rope released from connection to the donkey or other tightening mechanism. The device will then assume the position indicated by the dot and dash lines in Fig. 1.

It will be noted that the connection 6 of the device to the anchorage is offset from the line of the clamp 7, 8 so that when the rope 2 is tightened to its anchorage and is free from the tension of the donkey engine by which the tightening was effected, the line of the clamp will be drawn toward the line of the guy rope 2, that the rope round the sheave 4 encircles as much of the sheave 4 as is conveniently possible to derive the advantage of the friction therefrom.

This offset of the connection 6 from the line of the clamp 2 on the opposite side of the pulley 4 is regarded as an important feature of the invention.

Having now particularly described my invention, I hereby declare that what I claim as new and desire to be protected in by Letters Patent, is:

- 5 1. Means for securing a wire rope to its anchorage, said means comprising in combination, a grooved sheave adapted to take the wire rope to be tightened, side frames between which the sheave is rotatably mounted, a wire rope clamp secured to the frame on one side of the sheave, means preventing backward rotation of the sheave from the clamp, means connected to the side frames on the other side of the sheave for connecting the frames to an anchorage and a fair lead sheave removably mounted on said frame adjacent to said clamp.
- 10 2. Means for securing a wire rope to its anchorage, said means comprising in combination, a grooved sheave adapted to receive the wire rope to be tightened, side frames between which the sheave is rotatably mounted, which side frames are extended tangentially from one side of the sheave and have a wire rope clamp between them, means preventing rotation of the sheave backward from the clamp, and means offset from the line of the clamp for connecting the side frames to the anchorage.
- 15 3. Means for securing a wire rope to its anchorage, said means comprising a grooved sheave adapted to receive the rope to be tightened, said sheave having ratchet teeth adjacent its periphery preventing backward movement of the sheave, side frames between which the sheave is rotatably mounted, which frames are extended tangentially from one side of the sheave, a fixed clamp member between the tangentially extended portions of the side plates grooved to receive the wire rope, a fair lead removably connected to the end of the tangentially projecting portion of the side frames and adapted to retain the wire rope parallel to the clamp member, a movable clamp member pin-connected to the side frames adjacent the sheave, the free end of which clamp member is extended toward the tangentially projecting portion of the frame, said clamp member grooved to receive the rope, bolts pivotally connected to one clamp member, lugs on each side of the other clamp member adapted to receive the bolts and enable them to tighten one clamp member on the other, a pawl mounted on the side frames to engage the ratchet teeth of the sheave, and a shackle pivotally mounted between the side frames on the opposite side of the sheave from the clamp for connection of the device to an anchorage.
- 20 4. Means for securing a wire rope to its anchorage, said means comprising in com-

bination, a grooved sheave adapted to take the wire rope to be tightened, a frame recessed to receive said sheave in which recess said sheave is rotatably mounted, a wire rope clamping member pivotally secured to one edge face of the frame, means for drawing said clamping member toward the said edge face of the frame to clamp the slack end of the rope, and means preventing backward rotation of the sheave from the clamp, said frame having a portion provided with means to connect to an anchorage, said means being offset from the line of said clamping edge of the frame.

5. Means for securing a wire rope to its anchorage, said means comprising in combination, a grooved sheave adapted to take the wire rope to be tightened, a frame recessed to receive said sheave in which recess said sheave is rotatably mounted, a wire rope clamping member pivotally secured to one edge face of the frame, means for drawing said clamping member toward the said edge face of the frame to clamp the slack end of the rope, means preventing backward rotation of the sheave from the clamp, and a rope guide on one end of the frame over which the slack end of the rope passes for aligning the slack end of the rope with the sheave and clamp.

6. Means for securing a wire rope to its anchorage, said means comprising a grooved sheave adapted to receive the wire rope to be tightened, a frame having side members between which said sheave is rotatably mounted, said frame being extended with a face tangential to the periphery of said sheave, along which face the slack end of the rope lies, a movable clamp member carried by said frame and adapted to grip the slack end of the rope against the tangential face of the frame, a ratchet and pawl connection between said frame and sheave to prevent backward rotation of said sheave, and a guide sheave mounted on said frame over which the slack end of the cable passes for holding the slack end of the cable in alignment with the first mentioned sheave and clamp.

7. A means for securing a wire rope to its anchorage, comprising a frame, a grooved sheave in the frame, means preventing backward rotation of said sheave, a clamp for securing the slack end of the cable to the frame and means on the frame to connect the frame to an anchorage, said connecting means being located on the side of the sheave opposite to said clamp and opposite from the line of the clamp.

In testimony whereof I affix my signature.

WILLIAM GOETZ.
